UNITED STATES PATENT OFFICE.

CARL EBERHARD DRANGE, OF PLAINFIELD, NEW JERSEY, ASSIGNOR TO ISABELLA SCOTT AND DAVID J. SCOTT, EXECUTORS OF WALTER SCOTT, DECEASED.

MEANS FOR ATTACHING PRINTING-PLATES TO CYLINDERS.

1,360,378.

Specification of Letters Patent. Patented Nov. 30, 1920.

Application filed January 20, 1916. Serial No. 73,094.

To all whom it may concern:

Be it known that I, CARL E. DRANGE, a citizen of the United States, and a resident of Plainfield, in the county of Union and State of New Jersey, have invented certain new and useful Improvements in Means for Attaching Printing-Plates to Cylinders, of which the following is a specification.

This invention relates to printing machines employing flexible printing plates, such as rotary lithographic presses, and more particularly to means for placing flexible printing plates of the type shown in the companion application 64,956, Dec. 4, 15 1915, in position on the cylinders.

The size of presses using flexible metallic printing plates has increased with the beginning of the use of such plates in newspaper production. This has also necessitated an increase in the size of the plates themselves. Owing to the tendency of large and thin metal sheets to buckle, great difficulty has been experienced in placing the flexible plates in position on the cylinders. 25 An object of this invention is to provide means for rigidly holding the plates in a flat position until they are secured to the surface of the supporting cylinders.

This object is attained by providing a 30 transporting frame, or bed, for the flexible plate which is placed in horizontal position on a supporting table. The plate is clamped into position on the frame which is then bodily lifted to a vertical position and the 35 lower end thereof placed on carriers arranged to slide on vertical guide posts. When in this position the upper end of the frame is tilted against an adjacent plate cylinder whereupon the upper end of the plate 40 is secured in a slot or groove provided for the purpose in the face of the cylinder. By rotating the cylinder the plate is caused to wrap itself about the cylinder, the carriers meanwhile sliding upwardly along the guide 45 posts. This operation is continued until the lower end of the flexible plate has been brought opposite a corresponding slot in the cylinder whereupon the remaining end of the flexible plate is secured to the cylinder 50 to complete the placing of the flexible plate in position on the cylinder.

Other features of construction will appear as the specification proceeds.

In the accompanying drawings:

55 Figure 1 illustrates a view in side eleva-

tion of the supporting table on which the transporting frame is adapted to be placed in plate receiving position.

Fig. 2 is an end view partly in elevation and partly in section of the supporting table 60 illustrated in Fig. 1.

Fig. 3 is an end view partly in elevation and partly in section of a part of a rotary press showing the manner of supporting and securing the flexible plate in position on the 65 cylinder.

Fig. 4 is an enlarged view showing in detail the means for securing the upper end of the plate to the cylinder.

Fig. 5 is an enlarged view showing in detail one of the carriers for the lower end of the plate just after the sliding movement up the guide post has begun. 75

Similar reference characters refer to corresponding parts in the several views.

In the drawings 1 represents the lateral frame members of the table 2. The members 1 are rigidly connected by the rods 3. A bed 4 of wood or equivalent material forms the table top and has a cut-away portion 5 along the upper edge of either side which is adapted to receive a bar 6. The bars 6 form the side pieces of a transporting frame 7. Rods 8 serve to connect the side pieces of the frame together. Grooves 85 9, cut in the upper face of the table top are adapted to receive the transverse rods 8 when the frame is in position on the table. 80

A bracket 10 secured to the wooden bed 4 near the end of each lateral edge provides 90 a slot 11 between the upstanding members 12. The bars 6 are also provided with spaced members 13 which provide slots 14 which register with the slots 11 in the brackets 10 when the frame is in place on the 95 table. Handles 15 at the ends of the bars 6 form a convenient means for carrying the frame from place to place. Closely adjacent each handle is a notch, or groove, 16 the purpose of which will be hereinafter 100 explained.

Reinforcing means adapted to be clamped to each end of a flexible plate 17 are formed of the members 18 and 19. Screws 20 are employed to cause the members 18 and 19 105 to grip an end of the flexible plate therebetween. Tangs 21 rectangular in cross-section on the main clamping member 18 are adapted to fit into the slots 11 and 14 to hold the clamping members in position 110

while the end of a plate is being fitted into place therebetween.

In Fig. 3 is shown at 22 a base member on which the frame member 23, shown as 5 partly broken-away, is supported. Carried by the frame are the cylinders 24 and 25 one of which, as the cylinder 24, may be a form cylinder to which the flexible printing plates are applied.

10 Mounted in the base member 22 is shown at 26 one of a pair of guide posts on each of which is mounted a slidable support, or carriage 27. These supports take the form of sleeves from which extend lugs 28 forming between them a slot 29 adapted to receive the portion of the tangs 21 which has just been removed from the slots 11 in the table brackets 10. Projecting from each post 26 is an L-shaped lug 30 adapted to 15 support a frame piece 6 by engagement with the notches 16 already referred to. A supporting lug 36 fixed in each post is adapted to hold the sleeves at a convenient distance above the lugs 30 so that the tangs 21 can be easily inserted into the slots 29 when the frame is being supported on the lugs 30.

Formed in the periphery of the plate cylinder 24 are the slots 31 which communicate with enlarged openings or pockets 32 within 30 which are mounted devices 33 of the type shown in application Ser. No. 64956, already referred to, for securing the plate reinforcing members and for placing the plate in a state of strain.

35 The operation of the device is as follows: The transporting frame 7 is first placed in position on the table 2. The plate-end reinforcing members are then placed in position with their tangs fitting into the slots 40 11 and 14 in the brackets 10 and bars 6. A printing plate 17 is then laid on the wooden table top and the ends made secure between the clamping members of the reinforcing means.

45 The whole frame with the flexible printing plate secured thereto is then transported bodily, by means of the handles 15, to the press where the notches 16 are placed in engagement with the lugs 30 on the guide 50 posts 26. The frame is now swung to a vertical position on the lugs 30 as a pivot and the projecting portions of the tangs 21, which have previously occupied the slots 11 of the table, are placed in the slots 29 in the 55 slidable members 27.

The upper edge of the frame is swung to a position closely adjacent the cylinder 24 and the cylinder is rotated until a slot 31 is brought into a position near the upper end 60 of the printing plate. The reinforced end of the printing plate is next removed from the transporting frame and secured in position in the adjacent slot in the cylinder.

65 The frame can now be removed and a slow rotation of the cylinder will wrap the flexi-

ble plate closely and smoothly over the periphery thereof, the slidable members 27 rising on the posts 26 as the flexible plate is wound on the cylinder. When the lower end of the plate has been raised to a point 70 adjacent the other slot in the cylinder, the corresponding reinforcing means is removed from the members 27 and secured in position in the slot in the cylinder.

The straining devices 33 are now manipulated by means of the screws 34 which bear on the straining device operating dogs 35 to pull on opposite ends of the printing plate and thus hold the plate securely and immovably in place on the cylinder. 75

The method disclosed in this application is claimed in divisional application filed Sept. 29, 1916, No. 122,849.

What is claimed, is:

1. A device for attaching a flexible printing member to a cylinder comprising: a portable support, a cylinder, means for removably mounting said flexible printing member on said support in a position that will prevent buckling of said member, means 90 whereby said support may be moved to bring said member into a position where it may be attached to said cylinder, and means for transferring the flexible printing member from the portable support to the cylinder. 95

2. A device for attaching a flexible sheet metal printing plate to a cylinder comprising: a portable plate support, a cylinder, means for removably mounting said plate on said support in a flat position, means 100 whereby said support and said plate may be moved to bring said plate into engagement with said cylinder, and means for securing said plate to said cylinder.

3. A device for attaching a flexible sheet metal plate to a cylinder comprising: a rigid frame adapted to have a plate secured thereto, a pivotal support on which said frame can be tilted to bring said plate into engagement with said cylinder, and means for securing said plate to said cylinder. 110

4. A device for attaching a flexible sheet metal printing plate to a cylinder comprising: a portable frame, means for attaching said plate to said frame in a horizontal position, a support for said frame, means on one end of said frame for pivotally engaging said support whereby said frame may be tilted to a vertical position with the upper end adjacent the cylinder, and means for securing said flexible plate to said cylinder. 115

5. A device for attaching a flexible sheet metal plate to a cylinder comprising: means for securing one end of said plate to said cylinder, and means for maintaining the remaining portion of said plate in a substantially flat condition while the cylinder is rotated to wind said plate onto said cylinder. 125

6. A device for attaching a flexible sheet metal plate to a cylinder comprising: a sup- 130

port for said plate, means for bringing one end of said support into engagement with said cylinder and attaching the corresponding end of said plate to said cylinder, and 5 means for maintaining the free portion of said plate in substantially a fixed plane while the plate is being wound onto said cylinder.

7. A device for attaching a flexible sheet metal plate to a cylinder comprising: a support for said plate, a guide-way, a member movable along said guideway toward said cylinder, means for mounting said support on said guideway and securing one end of 10 said plate to said cylinder, whereby upon rotation of said cylinder the movable member will move along said guideway until the remaining end of said plate is brought into engagement with said cylinder.

20 8. A device for securing reinforcing members to the ends of a flexible sheet metal plate comprising: reinforcing means, a support, means on said support for removably holding said reinforcing means, and means 25 for securing the ends of said plate to said reinforcing means.

9. A device for attaching reinforcing members to the ends of a flexible sheet metal printing plate comprising: reinforcing 30 means for the ends of said plate, a framework, means on said framework for holding said reinforcing means, and means for securing the ends of said printing plate to said reinforcing means while said reinforcing 35 means are being held by said framework.

10. A device for attaching reinforcing members to the ends of a flexible sheet metal printing plate comprising: reinforcing means for the ends of said plate, a portable 40 frame, means for supporting said frame in a horizontal position, means on said frame coöoperating with means on said supporting means for holding said reinforcing means, and means for securing the ends of said 45 plate to said reinforcing means.

11. A device for attaching a flexible sheet metal printing plate to a cylinder comprising-

ing: means for securing one end of a plate to a cylinder, a sliding member adapted to have the remaining end of said plate secured 50 thereto and to hold said plate under tension while the cylinder is being rotated to transfer the plate thereto.

12. A device for attaching a flexible sheet metal printing plate to a cylinder comprising: 55 means for reinforcing the ends of a plate, a stationary support having means for holding said reinforcing means, a portable plate support having means for holding said reinforcing means, said portable support being arranged to be supported by said stationary support and to have the holding means thereon arranged to coöperate with the holding means on said stationary support to hold said reinforcing means while 60 65 a plate is being attached to said reinforcing means.

13. An apparatus for clamping a flexible sheet metal printing plate to a cylinder comprising: a stationary plate support, plate reinforcing members removably mounted on 70 said stationary plate support, a portable plate support removably positioned on said stationary plate support, means for attaching a printing plate to said reinforcing 75 members while said plate and said reinforcing members are held on said stationary plate support, and means whereby said plate with its reinforcing members may be removed from said stationary support by 80 means of said portable plate support and placed in such relation to a printing cylinder that said reinforcing members and said printing plate may be clamped to said cylinder without releasing the tension on said 85 plate.

Signed at Plainfield in the county of Union and State of New Jersey this 18th day of January A. D. 1916.
